Term of patent 14 years

(Cl. D58—6)

FIG. 3.

FIG. 5.

FIG. 4.

The cross-hatching in FIGURES 1 and 2 shows a contrast in surface texture.

The dominant features of my design reside in the portions shown in full lines.

We claim:

The ornamental design for a bottle or the like, as shown and described.
